UNITED STATES PATENT OFFICE.

CLARENCE B. FOWLER, OF NEW YORK, N. Y., ASSIGNOR TO WESTERN ELECTRIC COMPANY, INCORPORATED, OF NEW YORK, N. Y., A CORPORATION OF NEW YORK.

TELEPHONE SYSTEM.

1,271,883.

Specification of Letters Patent.

Patented July 9, 1918.

Application filed September 25, 1917. Serial No. 193,102.

To all whom it may concern:

Be it known that I, CLARENCE B. FOWLER, a citizen of the United States, residing at New York, in the county of New York and 5 State of New York, have invented certain new and useful Improvements in Telephone Systems, of which the following is a full, clear, concise, and exact description.

This invention relates to telephone systems, and more particularly to such systems of the central energy type in which the busy or idle condition of a telephone line is determined by the presence or absence of a 10 definite potential at the test terminals of 15 the jacks in which the lines terminate.

In systems of this character employing poly-station telephone lines where the called party is on the same line with the calling party and the answering plug of the cord 20 circuit is in the line jack of such a line, a busy test relay connected with the tip or testing strand of the calling end of the cord circuit must operate upon the engagement of 25 this testing conductor with the test terminal 30 of another jack connected with the same line to connect a source of tone supply to the test terminals of all jacks of the line through the sleeve of the answering jack. A tone is 35 then produced in the operator's receiver connected with the testing conductor. Such a busy test is known as a reverting busy test. In such systems, the operation of the busy test relay has not been entirely satisfactory even when employing relays especially 40 designed and constructed for such service. It is therefore the object of this invention to provide busy testing means in which the difficulties heretofore experienced are not encountered.

45 In accordance with this invention a busy test relay of ordinary construction under the conditions mentioned is more positive in operation than the relay heretofore employed, thereby insuring under various conditions of service, that the reverting busy test will at all times be obtained by the operator making such test.

For a more complete understanding of 50 this invention reference should be had to the following description considered in connection with the accompanying drawing, wherein Figure 1 shows a cord circuit containing one embodiment of this invention; Fig. 2 shows a modification of that shown 55 in Fig. 1; and Fig. 3 shows an ordinary poly-

station telephone line. For convenience, the like apparatus of Figs. 1 and 2 are designated by the same reference characters.

It is thought that this invention will be understood from a description of the operation of the systems disclosed in the drawings, and it will therefore be so described.

Assuming that the party at station A on the telephone line D initiates a call by removing his receiver from the switchhook, 65 the line relay 5 is actuated to cause the lighting of the line lamp 6. The operator, upon observing the lighted condition of the line lamp 6, inserts answering plug 7 of cord circuit C into jack 8 of line D, whereupon 70 the cut-off relay 9 and supervisory relay 10 are operated, the former disconnecting the line relay from the line and causing the effacement of the line lamp, and the operation of the latter preventing the lighting of an- 75 swering supervisory lamp 11, which is now short-circuited through the alternate contact of answering supervisory relay 10.

The operator may now actuate listening key 15, thereby connecting the operator's 80 telephone set 16 with the talking conductors of the cord circuit. The actuation of the listening key 15 also opens contact 17, removing a short circuit from resistance coil 18, which is thereupon included in the tip 85 or testing conductor 19 in series with the winding 20 of the repeating coil 21. The actuation of this listening key also closes contact 22, preparing a circuit for the connection of a source of tone supply to the sleeve 90 of the jack with which the answering plug is connected, and connects a busy test relay 23, which is common to a plurality of cord circuits through contact 24 with the testing conductor 19. When so connected the relay 95 23 is in parallel with the resistance coil 18 and winding 20 of repeating coil 21.

The operator, upon being advised that party A desires to be connected with party B, touches the tip of plug 30 to the sleeve 100 contact of another jack 31 of line D, in order to determine whether the line of party B is idle or busy. There is an answering jack for each station of a poly-station line and each station has a separate number, so that 105 when the called station is on the same line with the calling station, the operator has no knowledge of this fact until after testing the line. Upon the engagement of the tip of plug 30 with the sleeve of jack 31, relay 23 110

is operated over a circuit from battery through the alternate contact of supervisory relay 10, resistance 12, sleeve contacts of the answering plug 7 and line jacks 8 and 31, 5 tip contact of the plug 30, contact 24 of listening key 15, and the winding of relay 23 to ground. At the same time a click is produced in the operator's receiver 38. In systems heretofore employed, the winding of 10 the repeating coil 21 has been included in parallel with the busy test relay, but since the windings of repeating coils connected in the talking circuit must necessarily be of low resistance in order to be of the highest 15 efficiency for transmitting telephonic currents, the winding connected in calling tip conductor shunts so much current from the busy test relay that there has been considerable difficulty in providing a busy test relay 20 which would respond under such conditions. Resistance 18, which is connected in series with winding 20 of repeating coil 21 when the listening key is actuated, is of quite high resistance, so that when winding 20 and the 25 coil 18 are in series and are in multiple with the winding of the busy test relay, there will be less shunting of the current from the busy test relay. In this way, the busy test relay receives a larger amount of current 30 when testing the condition of the line with which the answering plug of the same cord circuit is connected and responds much more readily. In fact, this temporary increase of the resistance in shunt of the busy test relay 35 while making a busy test improves the operation to such an extent that the special relays heretofore used for this purpose may be replaced by relays of ordinary construction. Relay 23 in operating connects a 40 source of tone supply 33 in circuit with the operator's receiver 38 to produce a tone therein. This circuit may be traced from the source of tone supply 33 through the contact of busy test relay 23, contact of disconnect relay 36 (common to a plurality of cord 45 circuits), contact 22 of listening key 15, conductor 34, sleeve contacts of the answering plug 7 and the jacks 8 and 31, tip contact of plug 30, testing or tip conductor 19, contact 24 of listening key 15, induction coil winding 37 in the operator's telephone set, receiver 38, condenser 39, contact 35 of listening key 15, winding of calling supervisory relay 47, repeating coil winding 40 50 and battery to ground. Upon receiving this tone in the receiver, the operator is advised that the called party is on the same line with the calling party. The called party may then be signaled in any desired manner, and 55 connections between the calling and called parties may also be completed in any desired manner.

Assuming that the call is for a subscriber on another telephone line similar to line D, 60 the engagement of the tip of the calling plug

30 with the sleeve of the jack of that line, if busy, merely produces a click in the operator's receiver 38, and while relay 23 may operate, no tone is produced in the operator's receiver, for the answering plug of this cord 70 circuit is connected with the jack of another line. If the line tested is idle, no click is produced in the operator's receiver. The listening key 15 may then be restored to normal position and the plug 30 inserted in 75 the jack of the line, whereupon the calling supervisory lamp 46 is lighted and the cut-off relay of the line is operated. The called subscriber may then be signaled in any desired manner. The removal of the receiver 80 at the called station from its switchhook causes the operation of the calling supervisory relay 47, which opens its normal contact, removing the short circuit from about relay 45 and permitting its operation, and 85 closes its alternate contact, short-circuiting the lamp 46, which is thereby extinguished.

If, while the two telephone lines are connected for conversation, should the operator in supervising the connection actuate the 90 listening key 15, the resistance 18 will not be included in the tip conductor 19 for it is now short-circuited through the contact of relay 45. The actuation of the listening key, while connecting the operator's telephone 95 set 16 to the talking strands of the cord circuit, also causes the operation of disconnect relay 36 over a circuit from battery from the winding of disconnect relay 36, the contact 35 of listening key 15, ring contacts 100 of the calling plug 30 and the line jack of the called line, out over one side of that line through the substation apparatus and switchhook contact, back over the other side of the line, tip contacts of the line jack and the calling plug 30, tip conductor 19, contact of relay 45, and repeating coil winding 20 to ground. Relay 36, in operating, introduces a break in the lead through which the source of tone supply 33 is connected 110 with the sleeve of the jack into which the answering plug 7 is inserted. This prevents the changing of the test potential of the jack sleeves of the calling line, so that should another operator be making a busy 115 test on that line while the first operator is connected with cord circuit C, the second operator will receive the usual busy test indication.

In supervising this connection, the operator after obtaining the desired information may restore the listening key to normal position, thereby disconnecting relay 36 from the cord circuit. At the conclusion of the conversation, the subscribers restore the receivers to the switchhooks, causing the release of the answering and calling supervisory relays 10 and 47, which in releasing, remove the short circuits of the answering and calling supervisory lamps 11 and 46, which 130

are thereupon lighted to furnish disconnect signals. The operator may then withdraw the plugs from the jacks, restoring all apparatus to normal condition.

- 5 In the modification shown in Fig. 2, only the calling end of the cord circuit is shown. In this modification there is provided a resistance coil 50 which is common to a plurality of cord circuits and which, when the 10 listening key of any one of the cord circuits is actuated, is connected in the tip or testing conductor in series with the repeating coil winding 20. The portion of the circuit including the common resistance 15 50, when connected in the tip conductor, may be traced from the tip of the calling plug 30 through contact 51 of listening key 52, resistance 50, contact 53 of the listening key 52 and repeating coil winding 20. When 20 the listening key 52 is actuated, the source of tone supply 33 is connected with the test terminal of the jack in which the answering plug is connected through the contact of busy test relay 23 (actuated when the tip 25 contact of the calling plug 30 is brought into engagement with the test terminal of the busy jack), contact of disconnect relay 36, contact 54, listening key 52 and conductor 34.
- 30 It is believed that this brief description will serve to make the operation of the cord circuit of Fig. 2 clear, and that it will therefore be unnecessary to trace out in detail the complete operation.
- 35 What is claimed is:
1. In a telephone system, in combination, a telephone line terminating in a plurality of jacks, a cord circuit having a combined talking and testing conductor for engaging the test terminal of a jack to determine the idle or busy condition of the line, a busy test relay, a resistance coil, and a listening key actuated to connect the resistance coil in the combined talking and testing conductor and to connect the test relay with the testing conductor in parallel relation to the resistance coil.
  2. In a telephone system, in combination, a telephone line terminating in a plurality of jacks, a plurality of cord circuits each having a combined talking and testing conductor for engaging the test terminal of a jack to determine the idle or busy condition of the line, a busy test relay, a resistance coil common to a plurality of cord circuits, and a listening key actuated to connect the resistance coil in the combined talking and testing conductor, and to connect the busy test relay with the testing conductor in parallel relation to the resistance coil.
  3. In a telephone system, in combination, a plurality of poly-station telephone lines, each terminating in a plurality of jacks, a plurality of cord circuits, one of the cord circuits having its answering end connected 45 with a jack of one of the lines, a testing conductor for the calling end of each of the cord circuits, an operator's telephone set, a listening key for the engaged cord circuit for connecting the operator's telephone set therewith, a resistance coil common to the cord circuits connected in series with the testing conductor of the engaged cord circuit by the actuation of the key, a source of tone supply, a test relay connected with the testing conductor of the engaged cord circuit in parallel with the resistance coil by the actuation of the key and responsive to the engagement of the testing conductor thereof with the test terminal of another jack of 50 the engaged line to connect a source of tone supply in circuit with the receiver of the operator's telephone set.
4. In a telephone system, in combination, a plurality of poly-station telephone lines, each terminating in a plurality of jacks, a plurality of cord circuits, one of the cord circuits having its answering end connected with a jack of one of the lines, a testing conductor for the calling end of each of the cord circuits, an operator's telephone set, a listening key for the engaged cord circuit for connecting the operator's telephone set therewith, a resistance coil common to the cord circuits connected in series with the testing conductor of the engaged cord circuit by the actuation of the key, a source of tone supply, a test relay connected with the testing conductor of the engaged cord circuit in parallel with the resistance coil by the actuation of the key and responsive to the engagement of the testing conductor thereof with the test terminal of another jack of 55 the engaged line to connect the source of tone supply in circuit with the receiver of the operator's telephone set, a relay energized when the calling end of the engaged cord circuit is connected with the jack of another line, and a circuit established upon the energization of the last mentioned relay for preventing the connection of the resistance coil in the testing conductor.
5. In a telephone system, in combination, a poly-station telephone line terminating in a plurality of jacks, a cord circuit having its answering end connected with one of the jacks, a testing conductor for the calling end of the cord circuit, a repeating coil for the cord circuit having a winding connected in the testing conductor, an operator's telephone set, a listening key for connecting the operator's telephone set with the cord circuit, a resistance coil connected in series with the repeating coil winding by the actuation of the key, a source of tone supply, and a test relay connected with the testing conductor and in parallel with the resistance coil and the repeating coil winding upon the actuation of the key and responsive to the engagement of the testing conductor with the 60 65 70 75 80 85 90 95 100 105 110 115 120 125 130

test terminal of another jack to connect the source of tone supply in circuit with the receiver of the operator's telephone set.

6. In a telephone system, in combination, 5 a poly-station telephone line terminating in a plurality of jacks, a cord circuit having its answering end connected with one of the jacks, a testing conductor for the calling end of the cord circuit, a repeating coil for 10 the cord circuit having a winding connected in the testing conductor, an operator's telephone set, a listening key for connecting the operator's telephone set with the cord circuit, a resistance coil connected in series 15 with the repeating coil winding by the actuation of the key; a source of tone supply, a test relay connected with the testing conductor and in parallel with the resistance

coil and the repeating coil winding upon the actuation of the key and responsive to the 20 engagement of the testing conductor with the test terminal of another jack to connect the source of tone supply in circuit with the receiver of the operator's telephone set, a relay in the calling end of the cord 25 circuit energized while the cord circuit is connected with a telephone line, and a disabling circuit established upon the energization of the last mentioned relay to prevent the connection of the resistance coil in the 30 testing conductor when the key is actuated.

In witness whereof, I hereunto subscribe my name this 18th day of September, A. D. 1917.

CLARENCE B. FOWLER.
